[57] ABSTRACT

Throw stick game apparatus comprises a crossbar. A crossbar rest unit supports the crossbar substantially horizontally at a predetermined distance above the ground. A plurality of sticks are adapted to be thrown at the crossbar in an effort to knock it off the crossbar rest unit. A plurality of bores are provided in the side walls through which the sticks are inserted when not in use.

FIG. 6.

FIG. 7.

STICK THROWING APPARATUS AND TARGET

DESCRIPTION OF THE INVENTION

The present invention relates to throw stick game apparatus.

The principal object of the invention is to provide throw stick game apparatus of simple structure for providing a game of interest, enjoyment, skill and entertainment which is simple and easy to play.

In order that the invention may be readily carried into effect, it will now be described with reference to the accompanying drawing, wherein:

FIG. 1 is a schematic diagram of an embodiment of the throw stick game apparatus of the invention in stored condition;

FIG. 2 is a view, partly in section, taken along the lines 2-2 of FIG. 1;

FIG. 3 is a schematic diagram of an embodiment of a throw stick of the apparatus of the invention;

FIG. 4 is a longitudinal sectional view of the crossbar rest unit of FIGS. 1 and 2;

FIG. 5 is a schematic diagram illustrating the support of the crossbar by the crossbar rest unit, on an enlarged scale;

FIG. 6 is a schematic diagram of the crossbar rest unit of the apparatus of the invention supporting the crossbar play; and

FIG. 7 is a schematic diagram of a player about to throw a stick of the apparatus of the invention.

In the FIGS., the same components are identified by 30 the same reference numerals.

The throw stick game apparatus of the invention comprises a crossbar 1 (FIGS. 1, 2, 5 and 6). A crossbar rest unit 2 (FIGS. 1, 2, 4, 5 and 6) supports the crossbar 1 substantially horizontally at a predetermined 35 distance above the ground, as shown in FIG. 6.

The crossbar rest unit comprises a box having spaced upper surfaces 3 and 4 (FIGS. 1 and 6) having a shallow notch 5 and 6, respectively, formed in each (FIGS. 1, 4 and 6) for accommodating the crossbar 1 in play, as shown in FIG. 6.

The crossbar rest unit box stores the crossbar 1 out of play, as shown in FIG. 1, in a manner whereby the crossbar extends from opposite sides 7 and 8 of the box to permit carrying of the box via the crossbar.

A plurality of sticks 9, 10, 11 and 12 (FIGS. 1 and 2) are adapted to be thrown at the crossbar 1 in an effort to knock it off the crossbar rest unit 2.

The game of the invention is played by positioning the crossbar rest unit 2 on a supporting surface. The crossbar 1 is used as a unit measure to mark off a determined distance from the crossbar rest unit 2 and a line is provided at such distance. The crossbar 1 is placed

in the crossbar rest unit 2 in the manner shown in FIG. 6. The players then toe the line and throw the sticks 9, 10, 11 and 12 at the crossbar 1 in an attempt to knock it off the crossbar rest unit.

To win the game, a player must reduce his score from a determined number of points to zero. Each time the crossbar 1 is knocked off, the player reduces his points by 5. The points are reduced by 3 for each partial knock off.

When a player misses the crossbar 1, the nearest point of the throw stick to the nearest point of the crossbar rest unit 2 is measured in throw stick lengths. Each length is a point. A fraction of a stick length is also a point. All the measured points due to missing the crossbar 1 are added to the player's score.

The crossbar rest unit 2 may comprise plastic or any suitable material, as may the crossbar 1 and the throw sticks 9, 10, 11 and 12. The crossbar 1 may be provided in two connectable units for convenience of storage in the crossbar rest unit 2. Any suitable number of throw sticks may be utilized.

I claim:

1. Throw stick game apparatus, comprising a crossbar; a crossbar rest unit for supporting the crossbar substantially horizontally at a predetermined distance above the ground, the crossbar rest unit comprising a box having four side surfaces for storing sticks, two of said sides being parallel and having spaced upper edges, a hollow notch formed in each edge for accommodating the crossbar in play, said notch comprising an indentation in the edge of each of the two parallel sides, and a plurality of elongated sticks having a substantially constant cross-section adapted to be thrown from a distance at the crossbar in an effort to knock it off the crossbar rest unit.

2. Throw stick game apparatus as claimed in claim 1, wherein the crossbar rest unit box stores the crossbar out of play in a manner whereby the crossbar extends from opposite sides of the box to permit carrying of the box via the crossbar.

3. Throw stick game apparatus as claimed in claim 1, wherein the pair of spaced substantially parallel sides have bores formed therethrough for accommodating the sticks in the bores in extending position between the sides.

4. Throw stick game apparatus as claimed in claim 3, wherein each of the sides has an additional bore formed therethrough for accommodating the crossbar out of play therethrough.
